GEOPHYSICAL INSTRUMENT MOUNTING

Daniel Silverman and John L. Bible, Tulsa, Okla.,
assignors to Stanolind Oil & Gas Company,
Tulsa, Okla., a corporation of Delaware

Application May 12, 1939, Serial No. 273,323

10 Claims. (Cl. 265—1.4)

This invention relates to a mounting for geophysical instruments and more particularly to a mounting by which a geophysical instrument may be used without removal from the truck, boat or other transporting vehicle in which the geophysical instrument is carried. This invention is particularly applicable for mounting gravity meters although it is equally suitable for mounting a wide variety of geophysical instruments.

The usual geophysical instruments together with their auxiliary equipment are usually very large and heavy and yet are very sensitive and delicate so far as their force-responsive members and suspensions are concerned. This, therefore, causes difficulty in handling the instruments, since considerable effort must be exerted to move and place them while at the same time they must be handled carefully in order to avoid damaging the delicate parts. The usual method is to transport geophysical equipment in trucks equipped with tripods which can be projected through the floor of the vehicle to find support on the ground. After the tripod is in place the instrument is lifted to the head of the tripod and adjusted to the proper level and direction. This particular operation requires great manual labor, because of the weight and bulk of the instrument, and great care, since any slight mishap may cause serious damage to the instrument itself.

It is an object of this invention to provide a mounting for geophysical instruments by which they can be transported safely in vehicles and placed upon the supporting tripod without the necessity of manual handling and without danger of injury. Another object of our invention is to provide a mounting for a geophysical instrument which will minimize the mechanical labor necessary to place this instrument in the proper condition for use. Other and more detailed objects, advantages and uses of our invention will become apparent as the description thereof proceeds, read in conjunction with the accompanying drawings which illustrate one specific embodiment thereof.

Figure 1 is a plan view showing the general features of the geophysical instrument mounting.

Figure 2 is a front elevation showing part of the frame of the geophysical instrument mounting, and also showing the support of the geophysical instrument on the tripod above the floor of the vehicle.

Figure 3 is a detailed section of the carriage mounting and carriage showing the shock ab-

sorbing mount of the geophysical instrument on the carriage taken along the line 3—3 of Figure 1.

Figure 4 is a detailed plan view of the lower frame of the tripod showing the elevating gear mechanism.

Figure 5 is an elevation of the lower tripod frame without the gear mechanism.

Figure 6 is a detailed plan view of the center gear mechanism shown in Figure 4.

Figure 7 is a detailed elevation of the center gear mechanism shown in Figure 6.

Figure 8 is a detailed elevation of the worm drive assembly taken along the line 8—8 of Figure 4.

Figure 9 is a sectional elevation of the worm drive assembly taken along the line 9—9 of Figure 8.

Figure 10 is a plan view of the upper tripod showing the locations of the three contact points.

Figure 11 is a sectional elevation taken along the line 11—11 of Figure 10 showing in detail a movable contact point.

Figure 12 is another sectional view taken along the line 12—12 of Figure 10 showing in detail the fixed contact point.

Figure 13 is a plan view showing a modification of our geophysical instrument mounting.

Figure 14 is a detailed elevation of the modified geophysical mounting, taken along the line 14—14 of Figure 13.

Referring now to Figures 1 and 3, geophysical instrument 10 is mounted on carriage 11 and fastened thereto by eye bolts 12 and wing nuts 13 which engage slotted brackets 14 fastened to geophysical instrument 10. Carriage 11 comprises two cross bars 15, the ends of which are fastened to upper channel frames 16 of shock absorber assemblies 17 (Figure 3). Lower channel frames 18 are fastened to pedestals 19. Axles 20 of flanged wheels 21 are held in pedestals 19 while the flanged wheels 21 engage tracks 22 to provide mobility for carriage 11 and its supported geophysical instrument 10. The shock ab-

sorbing means 17 between upper channel frames 16 and lower channel frames 18 may be sponge rubber or other shock absorbing medium. Upon cross bars 15 of carriage 11 is located a circular track 23 on which are mounted roller bearings 24. The base of geophysical instrument 10 is equipped with circular flange 25 which corresponds to track 23 and guides geophysical instrument 10 about rollers 24 and prevents it from being dislodged from the rollers. Track 22 rests on floor 14 of the vehicle and extends from the

front of the vehicle up to the tripod head as far as possible, at which point the track is terminated by stops 26 to prevent further movement of the carriage wheels 21. The tracks 22 extend to such a distance that the carriage 11 carrying the geophysical instrument 10 is located over the tripod head as indicated by the dotted lines 10'. Moreover, cross bars 15 are sufficiently elevated above track 22 that the carriage is above the tripod head. Tracks 22 are long enough to permit carriage 11 with its geophysical instrument to be moved entirely clear of the tripod head and located at the front of the vehicle. In order to prevent the movement of the carriage 11 while the vehicle is in motion or after the geophysical instrument has been set in place on the tripod heads, the wheels are chocked by means not shown.

As will be seen from the plan view illustrated in Figure 1, the tripod head consists of two triangular frames of different size, the smaller frame being superposed on the larger frame. The larger tripod head is formed of three channels 27, 28 and 29 carrying vertical angles 30 which are welded in place at the juncture of the channels. These angles serve as guides for the three legs 31 and these legs 31 may be clamped in place by means of clamps 32. The clamps are operated by means of wing nuts 33, being normally urged to an unclamped position by springs 34. When the vehicle is in motion vertical angles 30 of lower tripod frame 27, 28 and 29 rests on the floor 74 of the vehicle and the tripod legs 31 are clamped in a raised position.

The upper triangle of the tripod head is composed of channels 35, 36 and 37. This triangle is held in shape by blocks 38 which may be welded to the channels. The frame 35, 36, 37 is supported above frame 27, 28, 29 by screw shafts 39 (Figure 2), the details of which will be described more fully later. Shown generally on frame 35, 36, 37 are contact points 40, 41 and 42 and hand wheels 43 and 44. Also shown generally is the center gear assembly for elevating and lowering frame 35, 36, 37 which is controlled by crank 45 and crank shaft 46 which passes through bearing 47 fastened to channel 29. This will also be described in more detail later.

Figure 4 of the drawings shows in greater detail the gear assemblies on frame 27, 28, 29. Across each corner of frame 27, 28 and 29 are angles 48 and 49 which are fastened to the channel frames 27, 28 and 29. Supported on angles 48 and 49 are bearing posts 50 bolted thereto by bolts 51. Supported within bearing posts 50 are worm wheels 52 which cooperate with worm screws 53 on shafts 54. Shafts 54 pass through bearings 55 and 56 and are keyed therein. The opposite ends of screw shafts 54 are equipped with beveled gears 57 which cooperate with the lower beveled gear 58, shown in Fig. 7. Wing bolts 59 cooperate with openings 59a in channels 27, 28 and 29, in which pins (not shown) are inserted.

Figures 6 and 7 show in greater detail the gear assembly at the mid-point of the lower tripod frame 27, 28 and 29. A plate 60 supported on angles 61 and 62 which in turn are fastened to the lower legs of the channels 27 and 28 supports shaft 63 shown by the dotted line in Figure 7. Worm shafts 54 pass through bearings 64 which are suspended from plate 60. Shaft 46 passes through bearing 65 which is supported on plate 60, and terminates in beveled gear 66. Beveled gear 67 cooperates with beveled gear 66

and is joined to beveled gear 58 by the common shaft 63.

Figure 10 shows the details of frame 35, 36 and 37. Angles 68, 69 and 70 support contact points 40, 41 and 42 and are fastened to channels 35, 36 and 37. Contact point 40 is a fixed contact point while contact points 41 and 42 are thrust bearings, as may be seen in Figure 11. The height of contact points 41 and 42 may be adjusted by rotating hand wheels 43 and 44 which are fastened securely to threaded shafts 71 (Figure 11) one of which passes through a threaded opening in angle 69 and the other through a similar opening in angle 70. Figure 12 illustrates the means of fastening the fixed contact point 40 to angle 68 by means of nuts 72 and 73.

In operation the geophysical instrument 10 is mounted on carriage 11 and fastened securely thereto by eye bolts 12 and wing nuts 13 which cooperate with slotted brackets 14 on geophysical instrument 10. The tripod head is rough leveled as indicated by levels 75 by means of pins (not shown) in holes 59a, one end of which rests on the floor 74 of the vehicle. The tripod is raised or lowered by hand to a roughly horizontal position and the pins fastened securely in place by wing bolts 59. When this has been accomplished, wing nuts 33 are loosened, thereby releasing springs 34 which will urge clamp 32 to an unclamped position and permit legs 31 to be lowered to the ground through openings in the floor 74 of the vehicle on which the mounting is carried. Legs 31 are driven securely into position, wing nuts 33 are tightened and the tripod head is thus secured in a roughly horizontal position. If desired, wing bolts 59 may then be loosened and the pins in holes 59a removed.

When the tripod head has been roughly leveled, carriage 11 bearing geophysical instrument 10 is moved forward along tracks 22 until it is in position above the tripod head and the wheels 21 of carriage 11 braced against stop 26. The wheels 21 are then chocked firmly to prevent movement of the carriage 11. The tripod legs 31, and particularly the rear tripod leg, should be low enough after it has been driven into position to permit the frame of carriage 11 to pass above it without obstruction. Geophysical instrument 10 is freed from carriage 11 by loosening the wing nuts 13 and removing bolts 12 from brackets 14, and oriented, if necessary, by swinging it in the proper direction. Rollers 24 on track 23 serve to permit this operation without the exertion of any great effort on the part of the operator and flange 25 prevents geophysical instrument 10 from disengaging from the rollers.

Frame 35, 36 and 37 of the tripod head is raised until the contact points 40, 41 and 42 contact the base of the geophysical instrument 10 and elevate it from carriage 11. This is accomplished by turning crank 45 which in turn revolves shaft 46 and beveled gear 66. Beveled gear 66 meshes with beveled gear 67 and causes it to revolve thereby revolving beveled gear 58 which is joined to beveled gear 67 through shaft 63. As beveled gear 58 turns it causes beveled gears 57 to revolve in turn which imparts a rotary motion to worm shafts 54. Worm screws 53 on shafts 54 mesh with worm wheels 52 causing them to turn screw shafts 39, thereby raising upper tripod frame 35, 36 and 37. Screw shafts 39, being engaged in threaded blocks 38 of upper tripod frame, raise the entire frame until the contact points 40, 41 and 42 contact geophysical

instrument 10 lifting it clear of the truck. Since all of the beveled gears 57, worm screws 53, screw gears 52 and screw shafts 39 respectively, are identical in shape and size geophysical instrument 10 will be raised in approximately the horizontal position which was obtained by rough leveling frame 27, 28 and 29.

The oriented geophysical instrument 10 resting on contact points 40, 41 and 42 is now carefully adjusted to a level position as indicated by levels (not shown) on geophysical instrument 10 by means of hand wheels 43 and 44. As has been pointed out contact point 40 is a fixed contact point while contact points 41 and 42 are movable contact points. By turning hand wheels 43 and 44 to the right or left as may be necessary, the contact points 41 and 42 may be raised or lowered by the operator until geophysical instrument 10 is accurately leveled. The readings can then be taken, the instrument lowered by lowering frame 35, 36 and 37 through a reverse manipulation of the gear mechanism previously described until the instrument 10 again rests on carriage 11. The screws 12 are readjusted in brackets 14, and wing nuts 13 tightened, thereby fastening geophysical instrument 10 securely on carriage 11. The chocks are removed and the carriage 11 with its geophysical instrument 10 is returned to the front of the vehicle on tracks 22 where it is again chocked in place. Wing nuts 33 are loosened, legs 31 elevated into position and fastened there by retightening wing nuts 33. The entire mounting may then be moved by means of the vehicle to another location. As has been pointed out the cross bars 15 of carriage 11 are mounted on shock absorbing means 17 thereby cushioning geophysical instrument 10 and preventing the injury to the delicate parts of the instrument.

In a modification of our mounting, the carriage and track for moving the geophysical instrument into place is eliminated, and the instrument carried above the tripod heads on shock absorbing supports. This is shown in Figures 13 and 14. Figure 13 is a general plan view of this arrangement, while Figure 14 is an elevation showing in more detail the method of mounting the geophysical instrument above the tripod assembly. It will be obvious that the various details shown in Figures 4, 5, 6, 7, 8, 9, 10, 11 and 12 are equally applicable to this modification, and are omitted for the sake of simplicity.

Referring now to Figure 13, the ends of cross bars 15 are fastened to upper channel frames 16, of the shock absorber assemblies 17 as before. Lower channel frames 18 are mounted on posts 80, which are fastened firmly to the floor 74 of the vehicle. Geophysical instrument 10, fastened to cross bars 15 as previously described by wing nuts 13, screws 12 and brackets 14, is located in the desired position above the double tripod head. When the vehicle is in motion, the delicate parts of the instrument are protected from damage by the shock proof mounting. When the instrument is to be used, it is only necessary to free the instrument from its fastenings, orient it by means of rollers 24, (after properly adjusting the base tripod) and raise upper tripod head until the contact points lift the geophysical instrument from its support. After proper level adjustment has been made, the instrument is ready for use. Other stationary means than the posts illustrated for supporting geophysical instrument 10 in position are contemplated within the scope of this invention and may include walls, angles, 75

brackets, etc. In all cases, however, a shock absorbing medium is interposed between the frame supporting the geophysical instrument and the stationary supporting means.

5 This modification is particularly applicable in locations where the length of the vehicle is insufficient to permit the installation of the movable carriage and track arrangement, and may also be used in those locations where access to 10 the rear tripod leg (for positioning it securely) is not a problem. It should be pointed out, however, that the angle at which tripod legs 31 are held must not be greater than will permit these legs to be drawn up into the vehicle without being interfered with or limited by the walls of 15 geophysical instrument 10.

It will be seen by the above that we have provided a mounting for geophysical instruments intended to be conveyed by vehicle which protects the delicate parts of the apparatus and yet at the same time permits the quick and easy adjustment of the instrument to the position in which it is to be utilized without great manual labor or hardship in moving the heavy bulky 20 portion of the instruments.

We claim:

1. A geophysical instrument mounting comprising a tripod having a fixed head and an adjustable head, a support for a geophysical instrument, means for adjusting said support to 30 position said geophysical instrument above said tripod, and means for elevating said adjustable head to support said geophysical instrument.

2. A geophysical instrument mounting comprising a tripod having a fixed head and an adjustable head, a shock-proof support for a geophysical instrument, means for adjusting said shock proof support to position said geophysical instrument above said tripod on said shock-proof 35 support, and means for elevating said adjustable head to support said geophysical instrument.

3. A geophysical instrument mounting comprising a tripod having a fixed head and an adjustable head, a shock-proof support for said geophysical instrument when not in use, means for adjusting said geophysical instrument above 45 said tripod, means for elevating said adjustable tripod head to lift said geophysical instrument from said support, and means for leveling said geophysical instrument on said adjustable tripod head.

4. A geophysical instrument mounting comprising a vehicle, a carrying support thereon for a geophysical instrument, shock-absorbing 55 means associated with said carrying support, a fixed support adapted to project through the floor of said vehicle into firm contact with the earth and means associated with one of said supports whereby the vertical separation between said two supports is decreased and the geophysical instrument is lifted free of said carrying support by the upper portion of said fixed support and is thus held in fixed relationship with the earth while in use.

5. A geophysical instrument mounting comprising a vehicle, a fixed support for a geophysical instrument, adapted to project through the floor of said vehicle into firm contact with the earth, a carrying support for said geophysical instrument, said geophysical instrument being 60 adapted to rest upon said carrying support above said fixed support, a raisable portion on said fixed support and means associated therewith for raising the raisable portion of said fixed support into contact with said geophysical instrument.

ment to lift said geophysical instrument free of said carrying support onto said fixed support.

6. A geophysical instrument mounting comprising a vehicle, a carriage therein to support said geophysical instrument, shock-absorbing means associated with said carriage, a fixed support adapted to project through the floor of said vehicle into firm contact with the earth, track means for moving said carriage into position with said geophysical instrument over said fixed support and means mounted on said fixed support for lifting said geophysical instrument free of said carriage.

7. A geophysical instrument mounting comprising in a vehicle a movable support for a geophysical instrument, a guide to direct translational movement of said support, a guide to direct rotational movement of said geophysical instrument on said support and a fixed support having means thereon adapted to lift said geophysical instrument free of said movable support.

8. A geophysical instrument mounting comprising a vehicle, a first support for said geophysical instrument, said support being carried by said vehicle, a second support for said geophysical instrument, said second support being adapted to project through the floor of said vehicle into fixed contact with the earth, guiding and supporting means for moving said first support carrying said geophysical instrument into a first position in which said first support is distant from said second support and into a second position in which said first support is above said second support, and means associated with one of said two supports for lifting said geophysical instrument free of said first support and onto said second support.

9. A geophysical instrument mounting comprising a vehicle, a first support for said geophysical instrument, said support being carried by said vehicle, a second support for said geophysical instrument, said second support being adapted to project through the floor of said vehicle into fixed contact with the earth, guiding and supporting means for moving said first support carrying said geophysical instrument into a first position in which said first support is distant from said second support and into a second position in which said first support is above said second support, guiding means associated with said first support for rotational movement and adjustment of said geophysical instrument and means associated with one of said two supports for lifting said geophysical instrument free of said first support and onto said second support.

10. A geophysical instrument mounting comprising a vehicle, a tripod having a fixed head and an adjustable head, legs for supporting said fixed head and projectable through the floor of said vehicle into firm contact with the earth, means for raising and lowering said adjustable head, a wheeled truck for supporting said geophysical instrument, shock-absorbing means on said truck for protecting said geophysical instrument, guiding means for directing said truck bearing said geophysical instrument above said tripod, means on said adjustable tripod head for supporting said geophysical instrument in a raised position above said truck, and means connected with said last-mentioned supporting means for adjusting the level of the supported geophysical instrument.
